Primary Examiner — Sandra Snapp

(74) Attorney, Agent, or Firm — Keisling & Pieper PLC;
Trent C. Keisling(57) **CLAIM**

The ornamental design for two-column wax melt, as shown and described.

DESCRIPTION

FIG. 1 is a perspective view taken generally from the front of a two-column wax melt showing my new design;

FIG. 2 is a front elevational view thereof with the opposite side being a mirror image thereof;

FIG. 3 is a side elevational view thereof with the opposite side being a mirror image thereof;

FIG. 4 is a top plan view thereof; and,

FIG. 5 is a bottom plan view thereof.
